ATTACHMENT FOR INTERNAL COMBUSTION ENGINES

Lester H. Messinger, Jr., Trumbull, Conn., assignor to Messinger Devices, Incorporated, Bridgeport, Conn., a corporation of Connecticut

Application April 8, 1936, Serial No. 73,232

12 Claims. (Cl. 123—124)

This invention relates to new and useful improvements in internal combustion engine driven motor vehicles.

The objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:—

Fig. 1 is a side elevational view illustrating an embodiment of the invention as applied to an automobile;

Fig. 2 is a view showing certain parts uncovered and in their normal relative positions and the view also shows the wiring diagram;

Fig. 3 is a view of the main control switch of Fig. 2 in another position;

Fig. 4 is a view similar to Fig. 3 but showing the parts of the main control switch in yet another position;

Fig. 5 is a sectional view taken substantially along the line 5—5 of Fig. 2;

Fig. 6 is a sectional view through the valve operating means of the invention;

Fig. 7 is a plan view of a pressure operated switch means employed; and

Fig. 8 is a sectional view through said switch means.

Referring in detail to the drawings, in Fig. 1 is shown a portion of an automobile including a dash 10 and the usual floor boards 11. In front of the dash there is shown a portion of a motor 12 to which fuel is fed as from a carburetor 13 through an intake manifold 14. The supply of fuel is controlled in the usual manner by a throttle valve 15 the stem of which is shown at 15a connected with an operating arm 16 extending to each side of the stem and at one end connected with a spring 17 the tendency of which is to return the throttle valve to closed position when moved therefrom.

Connected with the other end of the arm 16 is a rod 18 the connection being formed as by a pin 19 on the arm and an elongated slot 20 in the end of the rod. At its forward end this rod 18 is pivotally connected with an accelerator or throttle pedal 21 and a coil spring 22 is anchored at one end to the rod and at its other end to a stationary bracket 23 and serves to return the

rod and accelerator pedal to their full line positions when moved therefrom.

The mechanism thus far described may be either in the form shown or may be of any other desired or conventional construction. It is simply illustrated as a conventional arrangement in order that the construction and operation of the means of the invention may be fully described. Bolted or otherwise secured in any desired position on the automobile as, for example, on the dash 10 is a housing 24 containing a main switching mechanism generally designated 25 and a detailed description of the construction and operation of which will later be given.

This switching mechanism amongst its other functions controls a circuit to coils 26 of a solenoid magnet mounted within a housing 27 and the cores of said coils are shown at 28 as being secured (see Fig. 6) to the walls of the housing 27 by means of screws 29. The coils 26 may be held in place about the cores 28 by any suitable means as, for example, by being driven thereon. It is to be understood that while the coils 26 are shown as connected in series they may be connected in parallel.

Housing 27 is connected with the intake manifold 14 of the engine and in its lower portion the housing includes a port 31 through which air may be admitted directly to the manifold instead of through the fuel supply means or carburetor 13. Arranged in the port or opening 31 is a valve 32 the stem 33 of which extends through the lower end of the housing as clearly shown in Fig. 6 and the upper end portion of which extends into the space between the magnet coils 26.

To this upper portion of the stem there is secured an armature 34 adapted to be attracted by the electro-magnets and when so attracted adapted to turn the valve stem 33 and consequently the valve 32 shifting the valve to open position whereupon air will be admitted through port 31 to the manifold 14 between the engine and the carburetor. A spring 35 above the armature 34 has one of its ends anchored to the housing as at 36 and has its other end portion wrapped repeatedly around the upper end portion of the valve stem 33. This spring is purposely made of great length so as to exert a constant pressure and the spring tends to retain the valve in closed position and to return it to such position when moved therefrom.

Mounted on the housing 24 or otherwise suitably located are binding posts 37, 38, 39 and 40 respectively. These posts are insulated from the housing and from one another. Within the hous-

- ing is a shaft 41 rotatably mounting a bushing 30 on which is pivotally mounted a plate-like member 42 having up-turned ears 43 pivotally connecting it with the bushing. Also within the 5 housing and pivotally mounted on the bushing 30 is a second plate-like member or an armature 44 bent or off-set intermediate its ends, as at 45 (see Figs. 3 and 4) and this off-set intermediate portion embraces the bushing.
- 10 A member 46 has an end portion 47 extending between and guided by the upper portions of the ears 43 and extending over the off-set portion of the member 44 and beyond one end of said member. Passing through the member 46 and an 15 end portion of the member 44 is a bolt 48 surrounded by a spring 49 constantly tending to keep the member 46 against the member 44 but permitting said members to be pressed apart as shown in Fig. 3.
- 20 The member 46 carries a contact element 50 connected with the binding post 39 as by a wire 51 and the plate-like member 42 carries a contact element 52 connected with the binding post 40 as by a wire 53. Further member 42 carries 25 a contact member 54 connected with the binding post 38 as by a wire 55 and the armature member 44 carries a contact member 56 connected with the binding post 38 by a wire 57. Within one end portion of the housing 24 there is arranged 30 an electro-magnet 58, the coil of which is connected with the binding posts 37 and 39 by wires 59 and 60.
- A lead 61 connects the binding post 39 with the positive side of a battery 62, which may be 35 the usual automobile battery, while a lead 63 connects binding post 40 with a binding post 64 on the housing 27. Binding post 64 is connected with one of the coils 26 by a wire 65, the coils being connected by a wire 66 while the lead from 40 the coils is shown at 67 connected with a binding post 68 from which a lead 69 extends to a ground. From the binding post 38 a lead 70 extends to the ignition coil 71 of the automobile.
- Binding post 37 is connected with a pressure 45 operated switch 72 by a wire 73 and a ground connection for said switch is shown at 74. Switch 72 is shown in detail in Figs. 7 and 8 and the relation of the switch to the engine is shown more particularly in Fig. 1. This switch comprises 50 an outer casing in the form of a cast metal covering including a cup-like body portion 75 and a closure portion 76.
- Closure 76 carries a tubular extension 77 projecting into the body 75 and at, preferably four, 55 equally spaced points about its inner end such extension is provided with recesses 78 each receiving a small coil spring 79 and partially receiving a plug 80 resting on or engaging said springs and having sliding fit in the respective recesses. The wall 81 of the body has a tapped opening 82 therein the purpose of which will later be fully described. On its inner side such wall is provided with spaced lugs 83. A bellows 84 is disposed in the body 75 and its inner end 60 wall 85 is normally against the lugs 83 while its outer end portion is folded about and soldered or otherwise secured to an annulus 86 clamped between the open end of the body and the closure 76.
- 65 It is noted that the extension 77 of the closure together with the parts carried thereby are located within the bellows and therefor when the closure is in place the interior of the bellows is sealed with respect to the exterior thereof. The 70 springs 79 may keep the plugs 80 against the

inner wall of the bellows or just short of such wall in which latter case the resiliency of the bellows will be depended on to keep its inner wall against or in close relation to the lugs 83.

Threaded into the closure 76 and its tubular extension 77 is a plug 88 locked in place as by a Jamb nut 89 and extending through such plug 88 is a long binding post 90 having a laminated contact head 91 at its inner end. A nut 82 on the outer end portion of the binding post 90 is 10 adapted to draw the head 91 toward the tubular extension 77 whereby to clamp insulation 93 against the outer and inner ends of said extension to insulate the post 90 therefrom. From Fig. 8 it will be clear that the contact head 91 is arranged in opposing relation to a contact 94 carried on the inner side of the end wall 85 of the bellows, but that the bellows and the springs 79 with their plugs 80 tend to keep such contacts spaced apart. Lug 95 or other suitable means 15 may be provided for mounting the switch 72 in the desired position. The lead wire 73 is connected with the binding post 90 as by a clamp nut 96 on the binding post at the outer side of the nut 82.

Switch 72 (see Fig. 1) is connected to be responsive to the pressure of the water being circulated in the cooling system of the engine 12. A water pump 87 is driven from the engine as through gears (not shown) and through a connection 99 30 draws water from the lower end of a radiator 99a. Through a pipe line 100 the pump discharges into the water jacket of the engine. A nipple 102 connects an elbow 101 with the tapped opening 82 in the switch body. Therefore the pressure of 35 the coolant being circulated by pump 87 is acting on the bellows and owing to the particular hook-up shown the velocity pressure of the coolant is acting directly on the bellows.

It will be understood that the plate-like members 42 and 44 are mounted for pivotal movement together and separately about the shaft 41, such members moving with the bushing 30 about the shaft. To one side of said shaft between the plate-like members there is arranged a spring 45 103 having one of its arms connected with each of the members. The normal tendency of this spring is to move said members apart and to keep the contacts 50 and 52 separated. A spring 104 is arranged between the other end portion of member 42 and the bottom wall of the housing 24 and serves to prevent the members 42 and 44 pivoting freely around the shaft 41 in a direction to bring the contact 50 into engagement with the upper wall of the housing and to prevent the 55 contact 54 or an end portion of member 44 coming into engagement with the lower wall of the housing.

The spring 103 causes the off-set portion 45 of member 44 to press against the bushing 30 and 60 forcing downwardly on the member 42 causes the upper ends of openings 43a of the ears 43 of member 42 to bear downwardly on the bushing. Thus the spring causes the members 42 and 44 to lock themselves about the bushing 30. However, the bushing is free to turn about the shaft 41 so that at the proper times, as will later be described, the members 42 and 44 may rock together or relatively about the shaft without undue friction. If desired the openings 43a in the 70 ears 43 may be elongated as and for the purpose set forth in my application Serial No. 13,019, filed March 26th, 1935.

Extending through a wall of the housing 24 in alignment with one end portion of the member 75

42 is a push rod or member 105 shown as in the form of a bolt. This push rod is slideable through the wall of the housing and normally is disposed with its inner end in spaced relation to the member 42. A bell-crank 106 is arranged at the outer side of the housing being pivoted at 107 and connected at one end of this bell-crank is a rod 108, the said rod at its other end being connected to the rod 18 at 109.

10 In operation the throttle lever 21 is depressed in the usual manner against the action of the spring 22 to open the throttle valve and the valve 32 in the air port 31 remains closed so that there is no change in the normal operation of the engine while it is under load or with open throttle. As long as the engine is being operated at a speed sufficient to cause the pump 97 to maintain, on the fluid being circulated, that degree of pressure necessary to keep the bellows 84 compressed with the contact 94 in engagement with the contact head 91 the electro-magnet 58 is energized from the battery and is attracting the end portion of the plate-like member 44 so that the switch parts are held in the positions in which they are shown in Fig. 2 provided the engine is operating under load or with advanced throttle. The circuit of the magnet is from the battery 62 through line 61, binding post 39, wire 60, from the coil of the magnet through wire 59, binding post 37, wire 73 20 to binding post 90 of the switch 72 and the ground wire 74 of the switch.

30 It will be noted in Fig. 2 that the contacts 54 and 56 are in engagement and that the circuit between the ignition means 71 and the battery is closed. Further, contacts 50 and 52 are separated so that the circuit to the coils 26 controlling the air valve 32 is open and such valve is therefore closed. If the throttle mechanism is now released or retarded while the engine maintains the predetermined speed as, for example, if the automobile is coasting in gear and the engine is operating above a predetermined speed as when the vehicle wheels are driving the engine, the bell-crank 106 engages and pushes the rod 105 40 inwardly and it engages an end portion of the plate-like member 42 and rocks said member about its pivot shaft 41 in opposition to the spring 103.

45 Since the plate-like member 44 is being held against movement by the charged magnet 58 rocking of the member 42 will serve to separate the contacts 54 and 56 to open the ignition circuit and to bring contacts 50 and 52 into engagement closing the circuit to the coils 26 with the result that the armature 34 is attracted and against the action of spring 35 the valve 32 is 50 swung to open position. This admits air to the manifold between the engine and the carburetor and relieves any vacuum in the manifold. The air port 31 is large so as to admit sufficient air to supply the engine requirements and therefore fuel will not be drawn into the engine and there will be a free intake and exhaust of air by the engine.

55 No appreciable amount of vacuum is needed to take air into the engine through the port 31 and the opening of the valve 32 gives a "free wheeling" effect since the pistons of the engine do not have to work against vacuum. As air, substantially free of fuel is drawn into the engine when the valve 32 is open it will be clear that a considerable savings in fuel results.

60 Should the speed of the engine drop below that necessary to operate the pump in a manner to 65 maintain the necessary pressure on the fluid be-

ing circulated then the bellows 84 will expand carrying contact 94 away from contact 91 opening the circuit to the magnet 58. Such magnet being deenergized the plate-like member or armature 44 will be released and will rock about the pivot 41 in a direction to bring contact 56 5 into engagement with contact 54, thereby closing the engine ignition circuit, and carrying the contact 50 out of engagement with contact 52 10 opening the circuit to the coils 26.

15 While the parts are in the positions of Fig. 3, that is, with the ignition circuit open, the throttle mechanism retarded and the valve 32 open, should the throttle mechanism be advanced the bell-crank 106 will be carried away from the push rod 105 and the latter will move out of the housing 24 permitting the parts to return to the positions in which they are shown in Fig. 2. This return movement of the parts will be accomplished by the spring 104. It will be understood that when 20 the throttle is advanced the engine will be speeded up so that the pump will be operating at increased speed and the pressure of the fluid being circulated will be raised whereby the bellows 84 will be partly collapsed to bring the contact 94 25 into engagement with the contact head 91, thus again closing the circuit to the magnet 58.

30 When the throttle is retarded the speed of the engine drops and should the engine drop to a predetermined low speed (either while idling or 30 while operating slowly under load) the fluid being circulated by pump 97 will not be under sufficient pressure to keep contacts 91 and 94 in engagement so that the circuit to magnet 58 will be open and the magnet will not be energized. Under 35 such conditions retarding of the throttle lever will shift the push rod 105 inwardly and the entire switch mechanism 25 will rock about the shaft 41 into the position shown in Fig. 4. There it will be noted that contacts 54 and 56 are in 40 engagement so that the engine ignition circuit is closed but that the contacts 50 and 52 are spaced apart so that the circuit to the coils 26 of the magnet controlling the valve 32 is open. Therefore, the valve 32 will be closed and the 45 engine may idle in the usual manner.

50 Owing to the mounting of the contact carrying member 46 the push rod 105 may operate to rock the member 42 and bring the contact 52 into engagement with the contact 50 without applying sufficient pressure to the armature or member 44 55 to force said member away from the magnet 58. That is, when the contact 52 engages contact 50 it may push the same upward slightly tensioning the spring 49 which will yield as indicated in 55 Fig. 3.

55 From the foregoing it will be understood that with the disclosed means the valve 32 will open whenever the throttle lever 21 is retarded and the engine is being driven at a speed sufficient 60 to have the pump 97 force the pressure of the fluid it is circulating up to the point necessary to have the bellows collapsed to cause contact 94 to engage contact 91. Thus the valve may open while the automobile is coasting in gear or when the throttle lever is advanced and suddenly released as when shifting gears.

65 Obviously by loosening the jamb nut 89 and adjusting the plug 88 the position of the contact head 91 may be adjusted relative to the 70 contact 94 so that greater or less movement of the bellows will be necessary to bring the contact 94 into engagement with the contact head 91. It is preferred that the mentioned adjustment be such that the pressure of the fluid being 75.

circulated will act on the bellows to cause contact 94 to engage contact 91 whenever the engine is operating above idling speed and will be insufficient for the stated purpose when the engine is 5 idling.

The engine may idle in the usual manner since on the engine dropping below a predetermined speed contacts 91 and 94 separate and the valve 32 closes. Also such valve closes immediately the 10 throttle is advanced as this permits the push rod 105 to move outward or drop downward away from the member 42. It will now be clear that the device is automatic in its operation and requires no special attention on the part of the 15 operator and that the device will not cause stalling of the engine when the latter is operating at low speed.

While the present device provides for the saving of fuel as above noted attention is directed 20 to the fact that with the throttle closed and the engine being driven by the vehicle at a speed or speeds above idling speed, should the valve 32 be closed or not provided fuel would be drawn into the engine and cracked on coming into contact with hot parts thereof and then discharged 25 in the form of obnoxious gases. With the present arrangement this is largely prevented. It is also noted that the coils 26 as well as the coils 58 operate off the battery and by a constant 30 voltage so that said coils do not have to be built to withstand the fluctuating voltages delivered from the automobile generator.

The energizing of coils 26 and 58 by a constant current is very desirable so as to have a 35 constant magnetic pull and to obtain the constant current it is necessary to have constant voltage. Therefore in the present case the said coils are energized from the battery 62. While the pressure switch 72 is described as responsive 40 to the pressure of the fluid being circulated in the engine cooling system it will be clear that the pump might be the oil pump of the engine or might be a pump entirely distinct from either the water or oil pump of the automobile.

In connection with the operation of the device 45 it will be noted in Fig. 3 that the magnet 58 is energized and that the contacts 54 and 56 are spaced so that the ignition circuit is open and that the contacts 50 and 52 are in engagement so that the circuit to the valve actuating coils 26 is 50 closed. Now if the pressure of the fluid being circulated by the pump 97 drops below a predetermined point the parts of switch 25 will move into the relative positions of Fig. 4 and the 55 circuits will be reversed. That is, the ignition circuit will be closed and the circuit to the coils 26 will be opened so that the valve 32 will be closed and the engine will be idling.

When the parts are positioned as in Fig. 4 60 should the pressure of the fluid being circulated be increased the circuits will again be reversed as the parts will be drawn into the relative positions in which they are shown in Fig. 3. While the parts are as shown in Fig. 4 should the engine be speeded up without depressing the throttle lever as when the automobile starts down a grade the ignition circuit would be opened and the circuit to the coils 26 closed so that the valve 65 32 would be opened. However, should the throttle be advanced when the parts are positioned as shown in Fig. 4 the parts would shift into the positions in which they are shown in Fig. 2 and the valve 32 would be closed to have the 70 engine operate in the usual manner.

Having thus set forth the nature of my invention, what I claim is:—

1. The combination in an internal combustion engine, means including an electrically operated valve for stopping the flow of fuel to the engine, a constant voltage circuit to operate said valve, means controlling said circuit, a second constant voltage circuit included in said last means, and other means controlled by the engine speed and controlling the second mentioned circuit. 10

2. The combination with an internal combustion engine including a fuel supply means, an air port to admit air to the engine independent of the fuel supply means, an electrically operated valve normally closing said air port and adapted 15 on being energized to open the port, a constant voltage circuit to operate said valve, means controlling said circuit, a second constant voltage circuit included in said last means, and other means controlled by the engine speed and controlling the second mentioned circuit. 20

3. The combination with an internal combustion engine including a throttle lever, means including an electrically operated valve for stopping the flow of fuel to the engine, a constant voltage circuit to operate said valve, a second constant voltage circuit, magnetic means in the second constant voltage circuit and controlling the first constant voltage circuit, other 25 means controlled by engine speed and controlling 30 the second mentioned constant voltage circuit, and means controlled by the position of said throttle lever which also controls said first constant voltage circuit.

4. The combination with an internal combustion engine including a fuel supply means and a throttle lever controlling said means, means including an air port to admit air to the engine independent of the fuel supply means, an electrically operated valve normally closing said air 40 port and adapted on being energized to open the port, a constant voltage circuit to operate said valve, a second constant voltage circuit, magnetic means in the second constant voltage circuit and controlling the first constant voltage 45 circuit, other means controlled by the engine speed and controlling the second mentioned constant voltage circuit, and means controlled by the position of said throttle lever which also controls said first constant voltage circuit. 50

5. The combination in an internal combustion engine, a fluid circulating pump actuated by said engine, means including an electrically operated valve for admitting air to the engine substantially to the exclusion of fuel, and means responsive to the pressure of the fluid being circulated 55 which means controls a circuit to operate said valve.

6. The combination in an internal combustion engine, a throttle lever, a fluid circulating pump 60 actuated by the engine, means including an electrically operated valve for stopping the flow of fuel to the engine, a constant voltage circuit to operate said valve, switching means controlled by the position of said throttle lever and controlling said circuit, and means responsive to the pressure of the fluid being circulated which means also is adapted to render said switching means operative and inoperative. 65

7. The combination in an internal combustion 70 engine including a throttle lever, a fluid circulating pump actuated by the engine, means including an electrically operated valve for admitting air to the engine substantially to the exclusion of fuel, a constant voltage circuit to 75

operate said valve, switching means controlled by the position of said throttle lever and controlling said circuit, and means responsive to the pressure of the fluid being circulated which means also is adapted to render said switching means operative and inoperative.

- 5 8. The combination with an internal combustion engine including a fuel supply means and an ignition circuit, an air port to admit air to the engine independent of the fuel supply means, an electrically operated valve normally closing said air port and adapted on being energized to open the port, a fluid circulating pump actuated by the engine, means adapted to cause energizing of said valve and disruption of said ignition circuit, and means responsive to the pressure of the fluid being circulated which means controls the second mentioned means when the engine is being driven.
- 10 9. The combination with an internal combustion engine including a fuel supply means and an ignition circuit, an electrically operated valve adapted when energized to cause stopping of the flow of fuel to the engine, a fluid circulating pump actuated by the engine, means adapted to cause energizing of said valve and disruption of said ignition circuit, and means responsive to the pressure of the fluid being circulated which means controls the second mentioned means when the engine is being driven.
- 15 10. In combination with an internal combustion engine including a fuel supply and an igni-

tion circuit, an electrically operated valve adapted to open on being energized and admit air to the engine substantially to the exclusion of fuel, a fluid circulating pump actuated by the engine, means adapted to cause energizing of said valve 5 and disruption of said ignition circuit, and means controlling said first mentioned means and responsive to the pressure of the fluid being circulated by said pump.

11. The combination with an internal combustion engine including a fuel supply and an ignition circuit, an air port to admit air to the engine independent of the fuel supply, a valve normally closing said air port, a fluid circulating pump actuated by the engine, means to cause 15 opening of said valve and disruption of said ignition circuit, and means controlling the first mentioned means and responsive to the pressure of the fluid being circulated by said pump.

12. The combination with an internal combustion engine including a fuel supply and an ignition circuit, means to cause stopping of the flow of fuel to the engine, a fluid circulating pump actuated by the engine, means to cause actuation of said first means to stop the flow of fuel 25 to the engine and to cause disruption of said ignition circuit, and means responsive to the pressure of the fluid being circulated by said pump and controlling the second mentioned means.

30 LESTER H. MESSINGER, JR.
